US00D703312S

(12) **United States Design Patent**
Lubke et al.

(10) **Patent No.:** **US D703,312 S**
(45) **Date of Patent:** **** Apr. 22, 2014**

(54) **PATIENT INTERFACE**

(75) Inventors: **Steven John Lubke**, Stanmore (AU);
Rupert Christian Scheiner, Davidson
(AU); **James William Charles Vandyke**,
Glebe (AU); **Christopher Scott**
Skipper, West Ryde (AU)

4,267,845 A 5/1981 Robertson, Jr. et al.
4,273,124 A 6/1981 Zimmerman
4,312,359 A 1/1982 Olson
4,367,735 A 1/1983 Dali
4,367,816 A 1/1983 Wilkes
4,406,283 A 9/1983 Bir
4,422,456 A 12/1983 Teip

(Continued)

(73) Assignee: **ResMed Limited**, Bella Vista (AU)

FOREIGN PATENT DOCUMENTS

(***) Term: **14 Years**

DE 146688 2/1981
DE 37 19 009 12/1988

(21) Appl. No.: **29/418,360**

(Continued)

(22) Filed: **Apr. 16, 2012**

OTHER PUBLICATIONS

Related U.S. Application Data

(63) Continuation of application No. 29/347,672, filed on Apr. 6, 2010, now Pat. No. Des. 659,237, which is a continuation of application No. 29/258,792, filed on Apr. 28, 2006, now Pat. No. Des. 623,288.

Lubke et al., U.S. Appl. No. 29/347,672, filed Apr. 6, 2010.

3,905,361 A	9/1975	Hewson et al.
4,156,426 A	5/1979	Gold

FIG. 1 is a front perspective view of a patient interface according to our new design;

FIG. 2 is a reverse perspective view thereof;

FIG. 3 is a front view thereof;

FIG. 4 is a rear view thereof;

FIG. 5 is a top view thereof;

FIG. 6 is a left side view thereof; and,

FIG. 7 is a right side view thereof.

The broken lines represent environmental structure and are for illustrative purposes only; the broken lines form no part of the claimed design.
